BATH TUB

Lal Behari Roy, 4 Pusa Road, New Delhi 5, India
Filed July 10, 1964, Ser. No. 381,868
3 Claims. (Cl. 4—173)

This invention relates to a bathing device such as a bath tub and has for its principal object to propose such a construction that the bath water is relieved of the floating oily and frothy body washings as soon as such waste substances separate from the bather's body.

It is further the object of this invention that it should be possible to automatically remove the oily deposit from the bath tub, thereby saving the trouble of cleaning the bath tub after each bath.

It is further the object of this invention that it should be possible to regulate the temperature of the bath water in course of the actual bathing operation.

According to this invention the bath tub comprises a hollow outer-shell open at the top, a bath tub with outwardly turned and rounded edges placed inside the outer-shell and having a clearance between the bath tub and the outer-shell on all sides and the bottom of the bath tub, and a superimposed top resting securely on the edges of the outer-shell with the lower part falling in line with the walls of the bath tub, having symmetrical outwardly turned rounded edges like those of the bath tub, but leaving all round clearance (gap) between the edges of the superimposed top and the bath tub.

Thus, in accordance with one embodiment, the bathing device comprises a hollow outer-shell, bigger than the bath tub in all dimensions and having a drain-out pipe at the lower end of the sloping bottom, a bath tub having resting props under the outside bottom and placed inside the hollow outer-shell, and a superimposed top resting at the upper end on the edge of the hollow outer-shell and projecting inward horizontally for a few inches on all sides and then projecting downward, keeping in line with the walls of the bath tub.

The outer-shell has a sloping bottom with a drain-off pipe near the lower bottom end to be connected with the drainage system of the building.

The bath tub has a sloping bottom with an outlet pipe projecting downward and ending just above the drain-off pipe of the outer-shell; near the four corners and a few inches above the bottom of the bath tub are fitted four eyelets on the walls of the bath tub; in each eyelet there are fitted two jets which are connected by two separate pipes through two separate faucets with the cold-water and hot-water mains.

The faucet, connected with the hot water main, has one inlet and four outlets and is of such construction that, by operating the valve of the faucet, all the four outlets can be opened or closed simultaneously.

The faucet, connected with the cold water main, is of similar construction as the hot water faucet and operates in the same manner.

The faucets are placed at such a place on or near the bathing device that the bather can easily operate them from inside the bath tub and regulate the flow of the hot and cold water in the bath tub at will at the time of the actual bathing operation.

The outlet pipe of the bath tub is fitted to the bath tub by a socket which has a stopper that is used for closing or opening the socket of the bath tub as and when desired.

The bath tub has two main faucets for hot and cold water fixed on the shorter wall and above the outlet pipe; these faucets are connected to the hot and cold water mains by pipes.

When the superimposed top is secured to the outer-shell, the bath tub is enclosed within the outer-shell and

2

the bathing device gives the appearance of a single piece.

The bath tub and the superimposed top are both removable from the outer-shell by disjoining the hot and cold water pipes, so that the inner side of the outer-shell can be cleaned and refitted or the pipes and other fittings may be changed when necessary.

The outer-shell, the bath tub and the superimposed top are all made of sheet metal with the inner sides of the three pieces having highly polished and non-corrodible surfaces; the outer surfaces are protected by decorative and rust resisting paints or enamels.

It is obvious that other modifications can be made within the ambit and scope of my invention.

The invention will now be more fully described with reference to the accompanying drawing in which—

FIGURE 1 is a vertical section of the bathing device,

FIGURE 1A shows the transverse sectional view of the bathing device,

FIGURE 2 is a somewhat schematic representation showing the position of the faucets and pipe connections to the eyelets,

FIGURE 3 is a schematic sectional view showing the positioning of the hot and cold water jets.

Referring to the drawings, 1 is the outer-shell holding

25 the bath tub 2 in its hold with free space all round between the two to allow free flow of water spilling from the bath tub into the outer-shell, 3 is the water out-let pipe of the outer-shell. 4 shows the position of the eyelets four in number (two are shown and two are not shown) fitted near the four bottom corners of the bath tub and 5 and 6 show the alignments of the cold and hot water pipes for continuous supply of cold and hot water in the bath tub at the time of actual bathing operation. 7 shows the props on which the bath tub stands inside the outer-shell, and 9 shows the stopper for closing the outlet of the bath tub. 10 and 11 show the positions of the cold and hot water faucets meant for rapid filling of the bath tub with water of desired temperature before actual bathing operation. 12 shows the superimposed top which

40 fits securely on the edges of the outer-shell and falling in line with the bath tub. 13 and 14 show the bent ends of the bath tub and the superimposed top and they are meant for allowing the floating body washings and oily

45 matters to spill over into the outer-shell and keeping thereby the walls of the bath tub clean. 15 shows the all round gap between the edges of the bath tub and the superimposed top for allowing free spilling of bath water from all sides of the bath tub into the outer-shell. 16 and 17 shows the positions of cold and hot water jets

50 fitted into the eyelets. 18 and 19 show the cold and hot water faucets regulating flow of cold and hot water into the bath tub through the jets fitted into the eyelets.

Referring to the functioning of the bathing device, when the bather fills the bath tub by opening faucets 55 10 and 11, the water level in the bath tub can rise maximum to the level of the gap 15. The faucets 10 and 11 are closed when the water level in the bath tub is a little below the gap 15.

The bather now enters the bath tub. Some water spills 60 through gap 15 into the outer-shell 1 and drains out through outlet pipe 3. As shown best in FIGURE 1A, bath tub 2 is oval shaped in transverse section and (see FIGURE 1) the end walls slope inwardly. Hence, there is no flat bottom to which the water tends to cling, and

65 it flows downwardly and washes the entrained materials with it to the outlet pipe 3.

The bather now opens the cold water faucet 18 and cold water flows continuously into the bath tub 2 through the four cold-water jets 16 fitted in four eyelets 4. Consequently, water starts spilling through the gap 15 from the bath tub into the outer-shell resulting in drop of temperature of the water in the bath tub.

The bather now operates hot water faucet 19 in such a manner that the requisite amount of hot water flows into the bath tub 2 through jets 17 to raise, maintain or lower the temperature of the water in the bath tub 2 as desired by the bather himself in course of the bathing operation.

In the course of the bathing operation, frothy and oily body washings float on the surface of the bath water and as the bath water is continuously spilling over the gap 15, these oily and frothy floating matters also spill over gap 15 along with the bath water, keeping the walls of the bath tub and the bath water in the bath tub clean.

Thus, by proper manipulation of faucet 19, it is possible to increase, maintain or decrease at will the temperature of the bath water during the bathing operation and keep the bath water clean.

I claim:

1. A bathing device comprising, an outer shell, a bath tub mounted within said outer shell, said outer shell and said bath tub having peripheral top portions which present adjacent but spaced edge surfaces so as to provide a water discharge opening for the spilling of water over the top wall of said bath tub and into the space between said bath tub and said outer shell, said bath tub having a sloping outer bottom surface, and water supply means comprising a plurality of eyelets positioned in the bottom wall portion of said bath tub and each comprising two water jets and separate pipe and faucet means for hot and cold water connected respectively to the two jets of each of said eyelets.

2. A bathing device comprising, an outer shell, a bath tub mounted within said outer shell, said outer shell and

5 said bath tub having peripheral top portions which present adjacent but spaced edge surfaces so as to provide a water discharge opening for the spilling of water over the top wall of said bath tub and into the space between said bath tub and said outer shell, said bath tub having a bottom surface which is oval shaped transversely of the longitudinal dimension of the bath tub and the end walls of which slope downwardly toward each other whereby water tends to flow downwardly along the outer surface of said bath tub so as to carry entrained materials with it, and means to supply water to said bath tub below the water level.

10 15 3. A bathing device as described in claim 2 wherein said outer shell has a top flange portion which overhangs the top edge of said bath tub thereby to form said water discharge opening as a peripheral slot extending horizontally.
